BRAKE BEAM SHOE

Charles K. Stillwagon, Johnstown, Pa., assignor
to Davis Brake Beam Company, Johnstown, Pa.,
a corporation of Pennsylvania

Application November 8, 1937, Serial No. 173,296

2 Claims. (Cl. 188—212)

This invention relates to railway car truck
brake rigging, and more particularly to the brake
beams thereof.

The common way of supporting brake beams in
5 railway car trucks is by hangers that are sus-
pended from brackets attached to the car truck
side frames, the lower ends of the hangers be-
ing connected to brake heads secured to the ends
10 of the beams. More recently it has been proposed
to eliminate the hangers and hanger brackets
and to support the brake beams at their ends on
ledges or brackets associated with the side
frames. For this purpose the ends of the beams
15 are extended sufficiently to overlie the support-
ing ledges, and upper ledges are provided above
the beam ends to hold the beams down in place,
especially when the brakes are applied. However,
difficulty has been encountered in providing the
20 ends of the beams with satisfactory surfaces for
sliding engagement with their supporting ledges,
and it is therefore an object of this invention to
overcome this difficulty by attaching shoes of
the desired contour to the beam ends. Other ob-
25 jects are to protect the beam ends against wear
and to balance the beam.

In accordance with this invention a shoe is
mounted on each end of such a brake beam and
extends between the adjacent side frame ledges
30 for supporting the beam without any necessity
for hangers. The shoe is in the form of a body
of metal that receives the end of the beam and
has smooth ledge-engaging surfaces. It also pref-
erably has a lateral extension projecting toward
35 the beam. The shoe may either extend inwardly
along the beam far enough to support a brake
head, or it may be short so that the brake head
can be mounted directly on the end portion of
the beam adjacent the inner face of the shoe.

40 The invention is illustrated in the accompany-
ing drawings in which Fig. 1 is a fragmentary
plan view of a railway car truck and brake
rigging; Fig. 2 is an enlarged view of one end
of a brake beam with my shoe connected there-
45 to; Fig. 3 is a vertical section of the beam and
shoe taken on the line III—III of Fig. 2; Fig. 4
is a fragmentary inside view of a truck side frame
showing in vertical section the opposite end of
the brake beam and its shoe; Fig. 5 is a view sim-
50 ilar to Fig. 2, but of a modification with a brake
head attached directly to the beam; Fig. 6 is a
vertical section taken on the line VI—VI of Fig.
5; and Fig. 7 is a view similar to Fig. 6 of a modi-
fied brake head and manner of attaching it to the
55 brake beam.

Referring to Fig. 1 of the drawings, a railway
car wheel 1 is journaled in one end of a car
truck side frame 2 in the customary manner, and a
brake beam 3 is disposed in the usual location
and is actuated to apply and release a brake shoe
4 by a brake lever 5 to which a connecting rod 7
and a piston rod 8 are pivotally connected. The
brake shoe is carried by a brake head 9 con-
nected to the end portion of the brake beam. In-
stead of supporting the brake beam by hangers
5 passing through the brake heads and suspended
from brackets attached to the side frames, the
ends of the beam are slidably supported directly
by the side frames.

Accordingly, as shown in Figs. 1 and 4, each
side frame is provided with a pair of vertically
spaced beam supporting brackets or ledges 11
which may be formed in the frame or may pro-
ject laterally therefrom as integral or separate
elements. The two ledges of each pair are sub-
stantially parallel and are shown in Fig. 4 as ex-
tending substantially radially of the wheel, which
is the direction in which the beam moves in ap-
plying the brakes. The end portions of the brake
beam are extended outwardly far enough to pro-
ject between the ledges by which the beam is
20 supported and held in place vertically although
allowed to slide forwardly and backwardly be-
tween the ledges to apply or release the brake
shoe.

Although the shape or construction of the
brake beam is not important as far as this inven-
tion is concerned, the one illustrated is formed
from a single rolled bar having the cross-sec-
tional form shown in Fig. 3. The cylindrical por-
tion of this bar is cut away from the T portion
35 except at its ends, and the bar is then upset to
permit the cylindrical portion to be bowed out-
wardly to form the tension member of the one-
piece beam. It will be apparent that the irregu-
lar contour of the end portions of the beam is
40 undesirable and unsatisfactory as a bearing
against the ledges, and that the beam ends and
ledges would soon wear each other away if al-
lowed to engage each other.

45 It is a feature of this invention that suitable
bearing surfaces are provided between the beam
ends and the ledges to prolong their lives and to
insure smooth operation of the beam. Accord-
ingly, there is mounted on each end of the beam
50 a shoe 12 that compensates for the irregular con-
tour of the beam end and forms a satisfactory
bearing against the ledges. This shoe prefer-
ably consists of a body of metal adapted to re-
ceive and enclose the end portion of the brake
55

beam for which purpose it is provided with an opening conforming to the end section of the beam and extending inwardly from the inner end of the shoe, as shown in Figs. 2 and 3. The shoe 5 is provided with substantially parallel upper and lower faces for engaging an upper and lower ledge 11, respectively, between which the shoe slides.

Any convenient manner of attachment may 10 be used for fastening the shoe to the beam. In the shoe illustrated in Figs. 2 and 3 its outer end portion is provided with recesses 13 in which the heads of a rivet 14 are countersunk to prevent them from striking the ledges 11. The rivet 15 passes through the compression member of the beam for initially securing the shoe to the beam. Instead of a solid one-piece shoe, the shoe may be split along one side or be formed in two pieces fastened together around the beam end. The 20 inner end portion of the shoe is provided with openings 16 aligned with openings in the brake beam in which suitable fastening members 17 are inserted for connecting the brake head 9 directly to the shoe. For this purpose the brake head 25 is provided with parallel jaws adapted to slip over the parallel surfaces of the shoe, as indicated in broken lines in Fig. 3. The head can thus be removed without disturbing the shoe.

It is another feature of this invention that the 30 outer end portion of the shoe 12 is provided with an extension 18 projecting laterally towards the adjacent wheel, as shown in Figs. 2 and 4, to increase in that direction the length of the bearing area between the shoe and ledges whereby to aid in balancing the beam by preventing it from 35 tilting. This increased bearing area also causes the bearing surfaces of the shoe to wear more evenly instead of wearing rapidly at two diagonally opposite corners. As shown in Fig. 2, the 40 vertical end face 19 of the shoe is preferably arcuate to facilitate insertion of the beam between the ledges, it being the practice to first insert one end of the beam between one pair of ledges and to then swing the other end of the beam in between the opposite pair of ledges.

It will be understood from this disclosure that the irregular end portions of a brake beam are 45 enclosed by shoes having smooth bearing surfaces for engaging the ledges that support the beams. A further advantage is that all wear is taken up by the shoe, which can be easily and cheaply replaced, instead of by the brake beam. Also, the 50 form of the shoe aids in balancing the beam and preventing undue wear of shoe and ledges. In case it is desired to use brake hangers in addition to the ledges, the ledges would be curved

longitudinally to permit the beam to move in an arcuate path.

In the modification shown in Fig. 5 the shoe 21 is considerably shorter than the one just described so as to leave room for connection of 5 brake head 22 directly to the brake beam 3. The brake head is first slipped over the end of the beam and moved inwardly until in position to be secured to the beam, as shown in Fig. 6. Then the shoe is mounted on the end of the beam. Although the shoe must be removed before the head can be taken off the beam, this construction permits the use of heads of conventional design for this beam.

Fig. 7 shows a brake head 26 adapted to be 15 used with the short shoe 21 of Fig. 5, but this head is provided with jaws spaced far enough apart to allow the head to be slipped transversely over the beam after the shoe has been secured 20 in place. To steady the head on the irregular beam end, filled blocks 27 are used.

According to the provisions of the patent statutes, I have explained the principle and construction of my invention and have illustrated and described what I now consider to represent its best 25 embodiment. However, I desire to have it understood that, within the scope of the appended claims, the invention may be practiced otherwise than as specifically illustrated and described.

I claim:

1. The combination with a brake beam having ends of irregular cross section adapted to be supported by ledges associated with car truck side frames, of a shoe for each end of the beam provided with a recess for receiving the beam end to enclose it, said recess being irregular in cross section to conform to the shape of the beam end, and said shoe being provided with substantially parallel upper and lower faces for slidably engaging said ledges.

2. The combination with a brake beam having ends of irregular cross section adapted to be supported by ledges associated with car truck side frames, of a shoe enclosing each end of the beam and provided with substantially parallel upper 45 and lower faces joined at their inner ends by an inner face, a brake head mounted on the brake beam adjacent the inner face of each shoe, said head having substantially parallel jaws adapting the head to be slid transversely over the beam, 50 filler blocks mounted in the space between the parallel jaws and the irregular beam ends, and means for securing the head and blocks to the beam.

CHARLES K. STILLWAGON. 55
